UNITED STATES PATENT OFFICE.

GEORGE STROH, OF SYRACUSE, NEW YORK.

CASTING APPARATUS.

SPECIFICATION forming part of Letters Patent No. 759,568, dated May 10, 1904.

Application filed July 20, 1903. Serial No. 166,254. (No model.)

To all whom it may concern:

Be it known that I, GEORGE STROH, a citizen of the United States, and a resident of Syracuse, in the county of Onondaga, in the State 5 of New York, have invented new and useful Improvements in Casting Apparatus, of which the following, taken in connection with the accompanying drawings, is a full, clear, and exact description.

10. This invention relates to the class of casting apparatus in which artificial pressure is applied to the molten metal in the melting-pot to force said metal into the mold or matrix.

The chief object of the invention is to protect 15 the working parts of the apparatus from the intense heat applied to the apparatus during the operation thereof; and the object also is to provide a casting apparatus which shall have the component parts of its frame securely 20 united, so as to effectually guard against disturbance of their required relative position; and to that end the invention consists in the improved construction and combination of the frame of the apparatus and its appliances, as 25 hereinafter described, and set forth in the claims.

In the accompanying drawings, Figure 1 is a vertical longitudinal section through the center of an apparatus embodying my invention. Fig. 2 is a plan view of the said apparatus. Fig. 3 is a horizontal longitudinal section on line X X in Fig. 1, and Fig. 4 is a vertical transverse section on line Y Y in Fig. 1.

The apparatus comprises a cast-metal frame 35 composed of vertical side walls *a a* and an end wall *a'* and is preferably seated on a metal base-plate *A*. On the said frame is mounted a plate *b*, provided with an orifice *c*, the melting-pot *d* directly under said orifice, 40 the chute *e*, extending from said pot, preferably near the bottom thereof and ascendingly through the top plate; the inclined duct *f*, extending from the bottom of the pot and terminating in the cylindrical chamber *g*, the 45 transverse wall *h*, extending from said chamber to the top plate, and the valve-case *i*, having a vertical channel *i'* extending to the bottom of the lower end of the duct *f*, said parts being cast integral with the top plate *b* and all 50 sustained in position by rods *a'' a''*.

The orifice *c* is screw-threaded and has secured therein the threaded bottom portion of the discharge-nozzle *j*, which is provided with a flange *j'*, by which it is seated in a recess in the top of the plate *b*. The top of the nozzle 55 is preferably beveled to fit close to a correspondingly-beveled recess in a block *k*, secured in a mortise in the under side of a plate *P*, which is pivotally or otherwise removably supported on the top plate *b* of the frame. 60 The block *k* is provided with an orifice which registers with the mouth of the nozzle *j* and with an orifice *k'* in the plate *P*, upon which is mounted in any suitable manner the mold or matrix designed to receive the molten metal 65 from the melting-pot *d*. The metal to be melted is introduced into the pot *d* through the chute *e*, which is prolonged and provided near its outer end with a suitable cut-off valve *l* to prevent escape of heat through said duct 70 during the melting process.

The duct *f* is extended descendingly from the melting-pot *d* and is prolonged sufficiently to gradually recede from the heat applied to the melting-pot, and thus protect from excessive 75 heat the cylindrical pressure-chamber *g*, in which moves a plunger *D* for forcing the metal into the melting-pot *d* and expelling sufficient melted metal through the nozzle *j* to fill the mold or matrix mounted on the 80 plate *P*.

The plunger *D* may be operated by a lever *C*, pivotally connected to the frame of the apparatus, as shown at *C'*, or by steam or gas or hydraulic power. 85

The valve *I* in the case *i* must obviously be closed during the operation of the apparatus and is only opened when required to clean the melting-pot and the duct *f* and cylinder *g*.

O represents a combustion-chamber, the 90 main portion of which incloses the melting-pot and extends around the greater portion thereof. Said combustion-chamber is formed with an extension *O'* around the duct *f* and reduced in width, as shown in Fig. 1 of the 95 drawings, which extension serves to heat the said duct sufficiently to melt the metal contained therein preparatory to being forced into the melting-pot *d* by the action of the plunger *D*. The extension *O'* of the combust- 100

tion-chamber being terminated at the lower end of the duct, prevents excessive heating of the cylindrical pressure-chamber g , and thus obviates interference with the action of the 5 plunger D . The space O^2 , which is over the top of the pressure-chamber and communicates with the combustion-chamber, serves merely to receive the gases emitted from the combustion-chamber, which gases are allowed to escape through a pipe B , extended from the space O^2 .

$n\ n$ represent suitable burners, which communicate with the combustion-chamber O around the melting-pot d , so as to heat the 15 same to the required temperature to properly melt the metal in said pot. The burners are to be properly distributed around the melting-pot to heat it uniformly from all sides, and therefore the extra burner n' (shown in 20 Figs. 1 and 3) may be dispensed with.

$t\ t$ designate peep-holes through which to observe the temperature of the heat impinging the melting-pot.

What I claim as my invention is—

25 1. The combination with the melting-pot provided with a discharge-port at its top, of a duct tapping the bottom of the melting-pot and extended descendingly therefrom, a pressure-chamber communicating with the lower 30 end of said duct, and a plunger in said chamber as set forth.

35 2. The combination with the melting-pot provided with a discharge-port at its top, of a duct tapping the melting-pot and extended descendingly therefrom, a pressure-chamber connected to the lower end of said duct, and a waste-cock connected to the duct at its junction with the pressure-chamber as set forth.

40 3. The combination with the melting-pot, of a duct tapping the bottom of said pot and extending downward therefrom, a combustion-chamber inclosing the melting-pot and extended lengthwise of the aforesaid duct, a pressure-chamber connected to said duct remote from the melting-pot, and means for applying pressure to said chamber.

45 4. The combination with the melting-pot, of a duct tapping the said pot and extended descendingly therefrom, a combustion-chamber 50 inclosing the melting-pot and extended lengthwise of the aforesaid duct, burners communicating with the combustion-chamber adjacent to the melting-pot, a pressure-chamber connected to the lower end of the duct, and means for applying pressure to the interior of said chamber.

55 5. The combination with the melting-pot, of a duct tapping the bottom of said pot and extended descendingly therefrom, a combustion-

60 chamber inclosing the melting-pot and extended lengthwise of the duct, burners communicating with the combustion-chamber adjacent to the melting-pot, a pressure-chamber connected to the lower end of the duct, a plunger in said chamber, and a waste-cock connected to the duct adjacent to the pressure-chamber as set forth. 65

6. The combination with the melting-pot, of a duct tapping said pot and extended therefrom, a pressure-chamber connected to said duct remote from the melting-pot, a plunger in said chamber, a supply-chute extended descendingly to the melting-pot, a cut-off valve connected to the upper end portion of the chute, and a combustion-chamber inclosing 75 the melting-pot, and extended lengthwise of the aforesaid duct as set forth. 70

7. The combination with the melting-pot, of a duct tapping the bottom of said pot and extended descendingly therefrom, a pressure-chamber connected to the lower end of said duct, a plunger in said chamber, a supply-chute extended descendingly to the melting-pot, a cut-off valve connected to the upper end portion of the chute, and a combustion-chamber inclosing 80 the melting-pot and extended lengthwise of the aforesaid duct as set forth. 85

8. The combination with the melting-pot, of a duct tapping the bottom of said pot and extended descendingly therefrom, a pressure-chamber connected to the lower end of said duct, a plunger in said chamber, a waste-cock 90 connected to said duct adjacent to the pressure-chamber, a supply-chute extended descendingly to the melting-pot, a cut-off valve 95 connected to the upper end portion of said chute, a combustion-chamber inclosing the melting-pot and extended lengthwise of the aforesaid duct, and burners communicating with the combustion-chamber adjacent to the 100 melting-pot as set forth.

9. The within-described frame for metal-casting apparatus, consisting of side walls, and a top plate provided with an orifice, a pot directly under said orifice, a chute extending 105 from said pot through the top plate, an inclined duct extending from the pot and terminating in a cylindrical chamber, a transverse wall extending from said chamber to the top plate, and a valve-case having a vertical channel extending to the bottom of the lower end of the aforesaid duct all cast of metal as set forth and shown. 110

GEORGE STROH.
